CARTRIDGE LOADING MECHANISM FOR
BOLT ACTION GUNS

Alton M. Olson, Seattle, Wash.

Application June 23, 1950, Serial No. 169,947

4 Claims. (Cl. 42-17)

1

This invention relates to breech mechanisms for firearms.

In my Patent No. 2,479,770, issued August 23, 1949, there is disclosed and claimed a magazine assembly which holds cartridges in side by side relationship extending transversely of the longitudinal center line of the magazine and transverse to the bore of the associated rifle barrel. The present invention relates particularly to a breech mechanism for use with such a magazine assembly.

It is among the objects of the present invention to provide a breech or loading mechanism of the bolt action type which will receive a cartridge in crosswise position from the magazine, turn the cartridge to a bullet end first position and insert the cartridge into the chamber of the rifle barrel as the bolt is closed, which automatically elevates the cartridges into position to enter the barrel chamber as the cartridge is turned, which sets the firing pin for release by the trigger as the bolt is advanced or closed and ejects the cartridge shell when the bolt is opened or retracted, and which is simple and durable in construction, positive in operation and not subject to jamming or other malfunctioning in use.

Other objects and advantages will become apparent from a consideration of the following description and the appended claims in conjunction with the accompanying drawings wherein:

Figure 1 is a side elevational view of a fragmentary portion of a rifle having a breech or loading mechanism illustrative of the invention;

Figure 2 is a top plan view of the fragmentary portion of the rifle illustrated in Figure 1;

Figure 3 is a longitudinal cross sectional view on the line 3-3 of Figure 2;

Figure 4 is a bottom plan view of the fragmentary portion of the rifle illustrated in Figures 1, 2 and 3 with the forearm or forestock and magazine of the rifle removed;

Figure 5 is a bottom plan view of the bolt of the rifle;

Figure 6 is a side elevational view of a fragmentary portion of the rifle barrel and of the rifle bolt, loading mechanism and magazine, the forearm of the rifle being shown in longitudinal cross section;

Figure 7 is a cross sectional view similar to Figure 3 but showing the parts in a different operative position from that illustrated in Figure 3;

Figure 8 is a perspective exploded view of the components of the bolt operated loading mechanism of the rifle;

2

Figure 9 is a perspective exploded view of the bolt carried loading mechanism components; and

Figure 10 is a perspective view of a fragmentary portion of the rifle magazine.

With continued reference to the drawings, the firearm therein illustrated comprises, in general, a barrel 10, a receiver 11 joined to and extending from the breech or chamber end of the barrel, a breech bolt 12 slidably and rotatably mounted in the receiver 11 and having a handle 13, a stock including a forearm 14 in which the receiver and the adjacent portion of the barrel 10 are bedded, a screw 15 securing the barrel to the forearm, and a magazine 16 received in a magazine receiving space provided between the barrel and the forearm of the gun.

The receiver 11 is provided with a guideway 17 which extends from the end of the receiver remote from the barrel to a position intermediate the length of the receiver and is provided at its inner end with an offset 18. The bolt handle 13 is movable through the guideway 17 to slide the bolt in the receiver in its breech opening and breech closing movements and is receivable in the offset 18 to lock the bolt in breech closing position.

A firing pin 19 is mounted in the breech bolt 12 and a trigger 20 is pivotally mounted in the gun stock and provided with a sear 21 which engages a detent on the inner end of the firing pin to hold the firing pin in cocked position against the force of the firing spring until the trigger is pulled to release the sear from the detent. The firing pin can be released by the trigger only when the breech bolt is locked in breech closing position and the firing pin can also be locked in a safety position in which it cannot be released by the trigger. As this part of the mechanism is of known construction, a more detailed explanation is considered unnecessary for the purposes of the present disclosure.

Adjacent its barrel end the receiver 11 is provided with a lateral opening 22 through which the empty cartridge shells are ejected when the breech bolt is retracted after the gun has been fired and the opening 22 is extended across the side of the receiver adjacent the forearm 14 to provide a space through which cartridges may pass from the magazine into the receiver and in which the loading mechanism can operate. The receiver is also provided in its side adjacent the forearm 14 with a narrow slot 23 which extends from the end of opening 22 remote from the barrel 10 to a location adjacent the end of the receiver remote from the barrel, this slot varying in width along its length to accommodate differ-

ent components of the loading mechanism presently to be described.

The breech bolt 12 is provided in its side which is normally adjacent the forearm 14 with a longitudinally extending groove 24, this groove extending from the barrel end of the bolt to a location at the side of the handle 13 opposite the barrel end of the bolt and being widened at the location of the handle, as indicated at 25. A bridge 26 extends across the groove 24 at a location adjacent the handle 13 and between the handle and the barrel end of the bolt and several components of the loading mechanism, presently to be described, are mounted in the groove 24 near the barrel end of the breech bolt.

The hammer detent 27 engaged by the trigger sear 21 enters the end of the wider portion 25 of the groove 24 remote from the barrel end of the bolt and a rear bridge 28 is mounted in the wider portion of the groove adjacent the detent 27 so that the trigger sear will be depressed as the bolt is moved rearwardly or in its breech opening direction to free the bolt for such rearward movement.

A metal formation or loop 29 of generally rectangular shape is rigidly secured to the barrel 14 near the breech end of the barrel and is received in a recess provided in the forearm 14. This loop 29 is provided on its side remote from the barrel with an internally screw threaded boss or nut 30 into which the bedding screw 15 is threaded to firmly secure the barrel and the receiver to the stock and the forearm of the gun.

An elongated opening or recess 31 of rectangular cross sectional shape is provided between the barrel and the adjacent portion of the forearm 14 and the magazine 16 is received in this recess and passes through the loop formation 29.

The magazine 16 comprises an elongated casing 32 of rectangular cross sectional shape and having internal dimensions such that a cartridge of the proper type and calibre can be disposed transversely therein. Two blocks 33 are secured in one end of the casing 32, one at each side of the casing, and these blocks are provided on their inner ends with inclined ramps for guiding the cartridges through a longitudinally extending opening 34 in the top wall of the casing adjacent the blocks 33 and through the opening in the receiver 11 into the interior of the receiver when the magazine is operatively positioned in the rifle, as illustrated in Figure 3. The bottom wall of the casing is provided with a longitudinally extending slot and a magazine slide 35 is slidably mounted in this slot and has on its end adjacent the blocks 33 an abutment 36 which closes the corresponding end of the casing between the blocks 33. At its opposite end the slide 35 is offset, as indicated at 37, and is provided at its end with a returned portion 38 providing a finger grip. A tube 39 is secured at one end to the casing 32 opposite the end of the casing in which the blocks 33 are mounted, and a plunger 40 extends through this tube and the casing. A slide block 41 is secured on the end of the plunger 40 adjacent the blocks 33 and a coiled compression spring 42 surrounds the plunger between the slide block 41 and the outer end of the tube 39 and acts to resiliently urge the slide block toward the blocks 33. A sleeve 43 surrounds the tube 39 and is secured to the offset portion 37 of the slide 35 and a coiled compression spring 44 surrounds the tube 39 between the sleeve 43 and the adjacent end of the casing 32. A detent 45 is pro-

vided on the sleeve 43 and a lug 46 is provided on the rifle barrel to engage the detent 45.

When the magazine 16 is removed from the rifle the spring 44 expands moving the plunger 40 and slide block 41 outwardly of the casing until the outer end of sleeve 43 contacts a stop 47 secured on the tube 39 near the outer end of the latter. In this position of the magazine parts the abutment 36 is brought to a position adjacent to openings 48 disposed, one in each side of the casing 32. The ends of the abutment 36 are recessed so that cartridges can be forced through the openings 48 into the casing between the abutment 36 and the slide block 41. The cartridges are entered bullet end first into the casing and alternatively from opposite sides of the casing so that they are disposed in the casing transversely of the latter with their bullet ends at alternatively opposite sides of the casing. When the spring 44 expands the abutment 36 is moved up to cover the opening 34 so that the cartridges cannot move out of the magazine and, under these conditions, cartridges may be inserted into the casing 32 until the magazine is filled, the openings 48 in the sides of the magazine casing being positioned in registry with the recesses in the ends of abutment block 36 when the abutment block is in position to cover opening 34 in the top of the casing, as illustrated in Figure 10. When the desired number of cartridges have been placed in the magazine, the magazine is slid into the opening 31 in the forearm of the rifle to its limiting position and the sleeve 43 is then moved inwardly compressing the spring 44 and the detent 45 is engaged with the lug 46 on the rifle barrel to hold the magazine in operative position in the rifle. Compressing the spring 44 moves the abutment 36 to the rear of the opening 34 so that the bullets can now pass through the opening 34 in the magazine and the opening 22 in the receiver 11 into the interior of the receiver, the bullets being urged in this direction by the spring 42 acting on the slide block 41.

Each of the blocks 33 is provided with a recess opening to the end of the block at the adjacent end of the casing 32, as indicated at 49 and 50 in Figure 10, and two lugs 51 and 52 are secured to the receiver 11 at respectively opposite sides of the receiver and depend from the receiver adjacent the rear end of the opening 22. Forwardly projecting pins 53 and 54 are carried by the lugs 51 and 52 respectively at the lower ends of these lugs and these pins are received in the recesses 49 and 50 in the rear end of the magazine 16 to support the magazine in proper operative position in the rifle, the lugs 51 and 52 together constituting a stop for rearward movement of the magazine and holding the spring 44 under compression.

For a more detailed description of the magazine reference may be had to my Patent No. 2,479,770 referred to above.

The barrel 14 has at its breech end a reduced portion received in a socket 56 provided on the adjacent end of the receiver and a cartridge chamber 57 is provided in the barrel at the breech end of the barrel and communicating with the bore 58.

A very small hinge butt 60 (Figures 3 and 7) is secured to the bottom side of the receiver at the rear end of opening 22 and a cartridge guide 61 is pivotally connected intermediate its length to this hinge butt at the end of the hinge butt adjacent the opening 22.

The cartridge guide 61 comprises a pair of

hollow jaws 62 and 63 each of which has a side wall and two flanges extending perpendicularly from the opposite edges of the side wall. The flanges of each jaw extend inwardly toward the other jaw and at the corresponding side walls these flanges are spaced apart a distance such that the bullet end of a cartridge can pass between the flanges longitudinally of the corresponding side wall, but the rim end of a cartridge cannot pass between the flanges at this location. The flanges are triangular in shape so that the outer sides of the two jaws are inclined forwardly and inwardly, as illustrated in Figure 4, the guide thus being tapered from its rear to its forward end and having in its forward end an opening dimensioned to closely receive a cartridge, this forward end of the guide being disposed adjacent the cartridge chamber 57 at the breech end of the barrel. The two jaws 62 and 63 are spaced apart to provide a longitudinally extending slot 64 therebetween and are held in this position by a U-shaped structure 65 which extends rearwardly from the larger ends of the jaws 62 and 63 and has its ends joined one to each of these jaws. Lugs 66 and 67 are provided one on each leg of the U-shaped structure 65 adjacent the corresponding jaws 62 and 63 and are apertured to receive a pivot pin 69 which extends through the pin receiving formation on the forward end of the hinge butt 60. The bottom sides of the two jaws 62 and 63, that is, the sides of these jaws remote from the receiver 11, are recessed to provide an opening 68 (Figure 4) which extends transversely of the guide at the larger ends of the guide jaws 62 and 63 so that a cartridge passing through the opening 34 in the top wall of the magazine and through the opening 22 in the bottom of the receiver may pass through this opening 68 into the cartridge guide 61.

Two angle brackets 70 and 71 are secured to the bottom side of the receiver 11 to the rear of the rear end of the opening 22 in the receiver and have legs depending from the receiver in spaced apart, substantially parallel relationship to each other and disposed at respectively opposite sides of the slot 23 in the receiver. The U-shaped structure 65 has at its rear end an arched light 72 which extends downwardly from the legs of structure 65 substantially perpendicular to such legs and is received between the depending legs of the brackets 70 and 71 at the forward ends of the latter. By means of the hinge butt 60 and pin 69 the cartridge guide 61 is pivotally secured to the receiver for rocking movements so that its forward end can be positioned in alignment with the cartridge chamber 57 or positioned below this cartridge chamber and is firmly held by the angle brackets 70 and 71 and the arched structure 72 against twisting or turning movements which might throw the front end of the guide out of alignment with the rear end of the cartridge chamber.

A cartridge turning bar 73 has its forward end disposed between the two cartridge guide formations 62 and 63 and extends rearwardly between the depending legs of the angle brackets 70 and 71 being partly received in the slot 25 in the receiver. At its rearward end this turning bar is provided with an elongated loop formation 74 and a pin 75, which extends through a transverse aperture in the receiver, extends through the loop formation 74 to serve as a guide for the rear end of the turning bar and also to provide a limit stop for longitudinal movement of the bar

in both directions. A lever 76 disposed between the angle brackets 70 and 71 near the rear ends of these angle brackets and pivotally connected to the angle brackets by a pivot pin 77 extending through the angle brackets and the lever adjacent the bottom surface of the receiver 11, projects through the slot 23 in the receiver into the path of the bridge 26 on the bolt 12. A link 78, having a pair of spaced apart, substantially parallel sides, pivotally connects the lower end of lever 76 to the turning bar 73 at a location intermediate the length of the latter.

With this arrangement, when the slide bolt is moved rearwardly in a breech opening direction, 15 the bridge 26 engages the top end of lever 76 projecting into the receiver 11 through the slot 23 and moves this lever about the pivot pin 77 in a direction to force the turning bar 73 forwardly through the intermediacy of the link 78. With a cartridge in the guide 61 adjacent the opening 68, the forward end of the turning bar will engage this cartridge intermediate its length and force the cartridge forwardly in the guide. As the cartridge is forced forwardly in the guide 25 20 its rim end is retarded while its bullet end moves freely in a forward direction, the cartridge thus being turned bullet end first so that its bullet end will be presented to the rear end of the chamber 57 in barrel 10 when the bolt is moved to breech closing position.

A cartridge holder 80 is slidably mounted on the guide 61 and comprises a thin rectangular plate recessed to provide a generally U-shaped formation having two spaced apart, substantially parallel legs 81 and 82 which are slidably received in openings 83 provided one in the rear end wall of each of the guide formations 62 and 63 (Figure 8). Inwardly directed projections 84 and 85 are provided at the forward ends of the legs 81 and 82 and are spaced apart for the reception of the cartridge turning bar 73 therebetween. Two lugs 86 and 87 are provided at the rear end of the holder 80 and are disposed substantially at right angles to the legs 81 and 82. These lugs are recessed in their outer edges to receive the legs of the U-shaped formation 65 of the cartridge guide and the holder is recessed to provide an opening 88 between these lugs which opening extends to a location near the adjacent end of the opening 89 between the legs 81 and 82, the openings 88 and 89 being separated at their adjacent ends by a transverse bar formation 90. A pivot pin 91 extends across the opening 88 adjacent the bar 90 for attachment of the holder 80 to holder operating mechanism.

A lever 92 is disposed between the depending legs of the angle brackets 70 and 71 at a location ahead of the lever 76 and is pivotally connected at its lower end to the angle brackets by a pivot pin 93 which extends through the lever and through the depending legs of the angle brackets near the lower edges of the latter. A link 94 is provided at one end with a pin receiving formation 95 which receives the pivot pin 91 of the cartridge holder 80 and is provided at its opposite end with a pair of upwardly extending, spaced apart lugs 96 and 97 which are apertured at their upper ends and disposed one at each side of the lever 92. A pivot pin 98 extending through the apertures in the lugs 96 and 97 and through an aperture 99 in the lever 92 pivotally connects the rear end of the link 94 to the lever 92 near the upper end of the latter. At its upper end the lever 92 ex-

tends through the slot 23 in the receiver and into the path of the bridge 26 on the bolt 12.

A U-shaped yoke 100 has spaced apart legs which are pivotally connected at the open end of the yoke to the legs of the U-shaped structure 65 of the cartridge guide 61 near the corresponding guide jaws 62 and 63 and has its closed end slidably received in a slot 101 intermediate the length of the latter. At its rear end the pin 102 is pivotally connected to the depending legs of the angle brackets 70 and 71 by a pivot pin 103 and at its forward end this pin is provided with an abutment formation 104 (Figure 3). A coiled compression spring 105 surrounds the pin 102 between the abutment formation 104 and the closed end of the yoke 100 and resiliently urges the cartridge guide 61 downwardly to a position below the cartridge chamber 57 and clear of the bolt 12 when the bolt moves to its breech closing position.

With the above described mechanism, considering that a cartridge has been fired from the barrel chamber and the bolt is moved rearwardly to open the breech and eject the empty shell of the fired cartridge and then moved forwardly to reload the cartridge chamber and close the breech, as the bolt 12 moves rearwardly, the forward bridge 26 first contacts the end of lever 92 projecting into the receiver moving this end of the lever 92 rearwardly. This moves the cartridge holder 80 rearwardly in the cartridge guide 61 until the opening 68 in the guide is completely cleared permitting a new cartridge to enter the guide from the magazine 16 through the opening 36 in the magazine housing and the opening 22 in the receiver. A cartridge will now be fed from the magazine through the openings 34, 22 and 68 in the magazine, the receiver and the cartridge guide 61, respectively, by the feed spring 42 (Figure 3).

Upon continued rearward movement of the bolt the front bridge 26 passes over the adjacent end of lever 92 and contacts the end of lever 76 projecting into the receiver and moves the contacted end of this lever rearwardly. This moves the other end of lever 76 forwardly and advances the cartridge turning bar 73 in the cartridge guide turning the cartridge to a bullet end first position in the guide.

When the bolt 12 reaches its limiting rearward position in the receiver the cartridge turning bar is fully advanced but the front bridge does not overrun the adjacent end of the lever 76.

The direction of movement of the bolt 12 is now reversed and as the bolt moves forwardly the front bridge 26 again contacts the end of lever 92 projecting into the receiver and moves this end of the lever forwardly.

When the end of lever 92 projecting into the receiver was moved rearwardly by rearward movement of bolt 12 the end of link 94 was brought into engagement with this lever and a force exerted on pin 93 and lugs 96 and 97 to slightly bow the link 94. The link 94 is formed of resilient material, such as spring steel, and as soon as the bridge 26 overrides the lever 92 the link 94 straightens and springs the lever to a position in which its end will be engaged by the bridge 26 on the return stroke of the bolt.

As the bolt moves the contacted end of lever 92 forwardly this lever acting through the link 94 and associated pivots 91 and 98 advances the cartridge holder 80 in the cartridge guide 61 and

moves the cartridge to a position in which its bullet end is adjacent the forward end of the guide (Figure 7).

As the holder 80 is advanced the bar formation 90 of the holder engages the upwardly and forwardly inclined edge portions 125 and 126 on the legs 66 and 67 of the U-shaped structure 65 of the guide 61 positioned to the rear of and below the pivot pin 69 which pivotally mounts the cartridge guide 61 in the receiver 11. This causes the front end of the cartridge guide 61 to rise until it is in alignment with the barrel chamber 57 and the cartridge is positioned for engagement by a bolt carried pusher, presently to be described, which moves the cartridge from the guide into the barrel chamber.

With continued forward movement of the bolt, the rear bridge 28 engages the end of lever 76 projecting into the receiver and moves this end of the lever forwardly. This retracts the cartridge turning bar 73 to condition the guide 61 for the reception of a new cartridge from the magazine as soon as the holder 80 has also been retracted, as described above.

When the bolt 12 has reached a position in its forward movement at which the cartridge pusher 107 has engaged the rim end of the cartridge and moved the cartridge forwardly until its bullet end is entered into the barrel chamber 57, the front bridge 26 overrides the adjacent end of lever 92 releasing the pressure on this lever and on the cartridge holder 80. This discontinues the lifting pressure on the cartridge guide 61 permitting the guide 61 to move downwardly out of the way of the bolt 12 as the bolt pushes the cartridge fully into the barrel chamber and reaches its breech closing position.

The pusher 107 is a small body of U-shaped cross section pivotally mounted on a lug formation 107' at the front end of the bolt 12 and a link 108 is pivotally connected at its front end to the pusher 107 and extends rearwardly from the pusher along the under side of the bolt. An eye 109 is formed on the rear end of the link 108 and receives a pin 110 secured to the bolt by a bracket 111 and an apertured lug 112 is provided on the link 108 a short distance ahead of the eye 109. A guide pin 113 extends at its rearward end through the lug 112 and is secured at its forward end in the lug formation 107' on the bolt 12 to which the pusher 107 is pivotally connected. A coiled compression spring 114 surrounds the guide pin 113 between the lug 112 on the link 108 and the adjacent end of the lug formation 107' on the bolt and resiliently urges the pusher 107 to a retracted position in which its front end is substantially flush with the front end of the bolt and its bottom surface is positioned below the bottom of the front end of the bolt (Figures 5 and 7).

A cam lever 116 is pivotally mounted on the lug formation on the bolt and bears at its front end on the upper end of the cartridge pusher 107. A pair of detents 117, provided on the opposite end of this cam lever, ride on the bottom of the inside surface of the receiver and maintain the bullet pusher 107 in projected position while the bolt is being advanced to move the cartridge out of the cartridge guide 61. In its projected position the front end of the pusher 107 is in advance of the front end of the bolt and the bottom surface of the pusher is substantially flush with the bottom surface of the bolt 12 at the front end of the latter.

At the time the cartridge leaves the cartridge guide the detents 117 drop into the opening 22 in the receiver and this relieves the pressure of

the front end of the cam lever 106 on the cartridge pusher 107 and permits the spring 114 to move the cartridge pusher 107 to its retracted position in which its front end is below and substantially flush with the front end of the bolt 12. As the front end of the bolt reaches the rear or breech end of the barrel the pusher 107 is out of the way and the front end of the bolt is brought into direct contact with the rim end of the cartridge to firmly hold the cartridge in the cartridge chamber and provide for the impact of the firing pin against the rim end of the cartridge. The detents 117 now rest on the cartridge in the guide 61 and, upon the next loading action, the detents are raised when the guide 61 is raised and the cartridge therein moved forwardly to again advance the pusher 107 and position the detent 117 to pass over the hinge butt 60.

Upon the next retraction and advance of the bolt the cartridge then in the cartridge guide 61 will be placed in the cartridge chamber in the manner described above and a subsequent cartridge will be admitted into the cartridge guide. The gun may thus be reloaded by merely retracting and advancing the bolt until all of the cartridges in the magazine have been exhausted. Regardless of the end to end position of the cartridges in the magazine, they will be properly orientated in the cartridge guide and will always be presented bullet end first to the cartridge chamber.

Extractor hooks 120 and 121 are carried by the bolt 12 at the front end thereof and engage the rim of the cartridge in the cartridge chamber when the bolt is fully advanced. When the bolt is retracted these hooks pull the shell out of the cartridge chamber and when the front end of the bolt reaches the rear end of the opening 22 an ejector pin 122 carried by the bolt strikes the rim end of the cartridge and throws the cartridge out of the receiver through the opening 22.

Two spaced apart notches 118 are provided in the breech end of the barrel at the lower or forestock side of the barrel chamber. These are to receive the front end of a fixed ramp in case it is desired to mount a fixed ramp in the receiver in replacement of the movable guide hereinabove described and illustrated in the accompanying drawings.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A firearm loading mechanism comprising a receiver having at one end a formation providing a cartridge receiving chamber and having a guideway therein, a breech bolt slidable and rotatable in said receiver, a handle on said bolt movable through said guideway to guide said bolt in its breech opening and breech closing movements in said receiver, said receiver having an opening therein for admitting a cartridge from a magazine into said receiver with the cartridge extending transversely of the receiver, a cartridge guide in said receiver disposed between the cartridge admitting opening and the cartridge receiving chamber, said guide providing a cartridge passage

5 tapering from said opening to said chamber and restricted at its opposite sides to preclude the passage of the rim end of a cartridge along either side while permitting the free passage of the bullet end of a cartridge, a cartridge turning bar movable through said guide for turning a cartridge in the latter to present the bullet end of the cartridge to said chamber, means carried by said receiver and actuated by said bolt on breech opening movement of the bolt to advance said cartridge turning bar, a cartridge holder movable into said guide to hold a cartridge in properly turned position in the latter, means carried by said receiver and actuated by said bolt during the first part of the breech closing movement of the latter to advance said holder and operative during the remainder of the breech closing movement of said bolt to first elevate said guide to bring the chamber adjacent end of said guide into alignment with said chamber and then lower said guide out of the way of said bolt after a cartridge carried by the guide has entered the chamber, and to retract said cartridge turning bar and said cartridge holder, a pusher pivotally mounted on the chamber adjacent end of said bolt, and means carried by said bolt and engageable with said receiver to project said pusher during the latter portion of the breech closing movement of said bolt and retract said pusher just before the bolt closes to bring the end of the bolt into contact with the rim end of a cartridge forced into said chamber, said cartridge turning bar and said cartridge holder being fully retracted when said bolt reaches its breech closing position to permit passage of a subsequent cartridge through the opening in said receiver from a magazine into said cartridge guide.

2. In a firearm having a barrel provided at one end with a cartridge chamber, a receiver extending from the chambered end of the barrel, a breech bolt slidable and rotatable in the receiver and a magazine arranged to feed cartridges into the receiver in crosswise position relative to the receiver, loading mechanism comprising a cartridge guide pivotally mounted in said receiver and having an opening therein for receiving cartridges from said magazine, spring means resiliently urging said guide to a position below said chamber, a cartridge turning bar slidably mounted on said receiver and movable through said guide to turn and advance cartridges in said guide, bolt actuated means carried by said receiver and connected to said bar for advancing and retracting the latter, a cartridge holder slidably mounted on said guide, bolt actuated means carried by said receiver and connected to said holder for advancing and retracting said holder and raising said guide into alignment with said chamber when said holder is fully advanced, a cartridge pusher mounted on said bolt at the barrel adjacent end of the latter, spring means resiliently urging said pusher to retracted position, and means carried by said bolt and engaging said receiver and said pusher to project said pusher to operative position as the bolt approaches its breech closing position and to retract said pusher as the bolt reaches breech closing position.

3. In a firearm having a barrel provided at one end with a cartridge receiving chamber, a receiver extending from the chambered end of said barrel, a breech bolt slidably mounted in said receiver for movement toward and away from the adjacent end of said barrel, and a magazine mounted adjacent said receiver and arranged to feed car-

tridges into said receiver in cross wise position relative to the latter, loading mechanism for successively receiving cartridges in crosswise position in said receiver, turning the cartridges to bullet end first position and entering them into said cartridge chamber comprising a cartridge guide pivotally mounted in said receiver with one end adjacent said firing chamber and movable between a position in which said one end thereof is in alignment with said firing chamber and a position in which said one end is below said firing chamber, said guide being effective to receive the cartridges one at a time in crosswise position and turn them to a bullet end first position as the cartridges are advanced through the guide and having an opening at said one end thereof for delivering the cartridges into said firing chamber, bolt actuated means carried by said receiver and movable relative to said guide to advance a cartridge through the guide and raise said one end of the latter into alignment with the firing chamber, and bolt carried means engaging a cartridge in said guide when the latter is in raised position and moving the cartridge out of the guide and into said firing chamber as said bolt is moved into closing relationship with the adjacent end of said barrel.

4. In a firearm having a barrel provided at one end with a cartridge receiving chamber, a receiver extending from the chambered end of said barrel, a breech bolt slidably mounted in said receiver for movement toward and away from the adjacent end of said barrel, and a magazine mounted adjacent said receiver and arranged to feed cartridges into said receiver in crosswise position relative to the latter, loading mechanism for successively receiving cartridges in crosswise position in said receiver, turning the cartridges to bullet end first position and entering them into said cartridge chamber comprising a cartridge guide pivotally mounted in said receiver with one end adjacent said firing chamber and mov-

able between a position in which said one end thereof is in alignment with said firing chamber and a position in which said one end is below said firing chamber, said guide being effective to receive the cartridges one at a time in crosswise position and turn them to a bullet end first position as the cartridges are advanced through the guide and having an opening at said one end thereof for delivering the cartridges into said firing chamber, bolt actuated means carried by said receiver and movable relative to said guide to advance a cartridge through the guide and raise said one end of the latter into alignment with the firing chamber, and bolt carried means engaging a cartridge in said guide when the latter is in raised position and moving the cartridge out of the guide and into said firing chamber as said bolt is moved into closing relationship with the adjacent end of said barrel.
